FIG. 3

UNITED STATES PATENT OFFICE

JOHN WILLIAM GIES, OF NEW YORK, N. Y., ASSIGNOR TO OTIS ELEVATOR COMPANY,
OF NEW YORK, N. Y., A CORPORATION OF NEW JERSEY

MOVING STAIRWAY

Application filed May 20, 1930. Serial No. 453,956.

This invention relates to moving stairways, and is more particularly directed to improving and simplifying the maintenance of such stairways.

Moving stairways, similarly as floors and stationary stairways, are recipients of all forms of dust, dirt and trash. In certain installations of moving stairways, for example, those in subway and elevated railroad stations, where the amounts of dust and dirt deposited thereon are large, some of this dust and dirt may manage to get into the area where the working parts of the stairway operate, and even to get upon the working parts themselves. It is of course undesirable that dust, grit or other foreign matter which may become deposited upon friction areas of working parts should remain upon such areas, as friction and wear are increased if the stairway is operated with such foreign matter present upon the friction areas. The dust, dirt and other foreign matter in such installations also may become deposited upon other areas of the working parts, and although its presence there may not directly impede the operation of the moving stairway, this matter may later drop off and become deposited upon the friction areas. In addition, it has been found that such dust, dirt and other foreign matter that may collect upon the non-friction areas of the working parts may, in certain installations, collect in the form of an inflammable fuzz. To clean the working parts of such moving stairways, it is usually a manual task that not only is time-consuming, but, for thorough work and for safety, ordinarily involves taking such moving stairways out of service.

Moving stairways as at present constructed include numerous parts and surfaces that benefit from regular lubrication. To lubricate certain of these parts and surfaces, it is usually, as with the cleaning, a manual task that is time-consuming and that, for effectiveness and safety, ordinarily involves taking such moving stairways out of service. In fact, it is practically impossible to manually clean and lubricate the moving stairway except when it is stationary. In certain installations, however, where the moving stair-

ways are operated continuously for many hours every day in the week, as in heavy-traffic subway and elevated railroad stations, it is desirable not to take a moving stairway out of service at any time during the period when normally it is in operation, even for cleaning or for lubrication.

One feature of this invention is the provision of means by which a moving stairway may be readily and effectively cleaned while the stairway is in operation, and without danger to human life.

A second feature of this invention is the provision of means for quickly, thoroughly and positively lubricating vital parts of a moving stairway while the stairway is in operation, and effective, coincidentally, to conserve lubricant and to prevent injury to the worker applying the lubricant.

Other features and advantages will become apparent from the specification taken in connection with the accompanying drawings wherein one embodiment of the invention is illustrated.

In the embodiment of the invention to be described, a moving stairway is provided with a plurality of sets of air nozzles, each set being appropriately positioned for effecting the removal of dust, dirt and other foreign matter from some moving part of the stairway by means of the flow of air from the air nozzle. Thus, one set of cleaning air nozzles is provided for cleaning the driving chains and a second set of cleaning air nozzles is provided for cleaning the toe-guard and the underside of each step. There is also provided a plurality of lubricating nozzles, each adapted to emit a fine spray of oil, appropriately mounted so as to direct the oil sprays upon certain of the moving parts of the stairway. Thus, a set of lubricating nozzles is provided for effecting lubrication of the inside or step trailer wheels of each moving step and a second set of lubricating nozzles is provided for effecting lubrication of each driving chain, each step chain wheel, and each supporting axle for the step chain wheels.

In the drawings:—

Figure 1 is a schematic view in elevation

of the lower landing of a moving stairway illustrating the preferred placements for the cleaning and lubricating nozzles provided in accordance with this invention;

5 Figure 2 is a schematic plan view illustrating diagrammatically the manner of cooperation of the cleansing and lubricating apparatus with the driving chains and the moving steps;

10 Figure 3 is an end view taken along the line 3—3 of Figure 1 showing the apparatus for effecting lubrication of the driving chains, the step chain wheels, and the step chain wheel axles;

15 Figure 4 is a sectional view taken along the line 4—4 of Figure 1 showing the apparatus for effecting lubrication of the step trailer wheels;

20 Figure 5 is a sectional view taken along the line 5—5 of Figure 1 showing the apparatus for cleaning the steps and the driving chains;

25 Figure 6 is a sectional view of an air nozzle which has been found satisfactory for the purposes of this invention; and

30 Figure 7 is a sectional view of an oil-spraying nozzle which has been found satisfactory for the purposes of this invention.

Referring to the drawings, there is schematically shown in Figure 1 the lower landing of a moving stairway. The driving chains 11 and the moving steps 12 which are driven thereby reverse their direction of travel at the lower landing by running around suitable sprockets provided upon a movable carriage 13 at the lower landing. For simplicity, the sprockets and the movable carriage are shown only schematically. The movable carriage is adapted to roll upon the track 14 as a result of being provided with the rollers 15. The movable carriage is urged leftwardly, as shown in Figure 1, by means of a counterweight 16 for maintaining the driving chains and the series of steps taut. Each step is provided with four wheels. 40 Two of these wheels 17 are positioned between the links of the driving chain at either side of the step, so that as a result they are designated the chain wheels. The other two wheels 18 are positioned in vertical planes 45 different from those in which the chain wheels operate, and are designated the step trailer wheels. Each pair of chain wheels is connected to the front end of its corresponding step while each pair of step trailer wheels is connected to the step riser 20 for 50 its corresponding step. The step riser 20 is provided with a solid plate 21 across the width of the step. This plate 21 is commonly known as the toe-guard. Bars 22 connect the axles for the step trailer wheels with the axles for the chain wheels.

55 A pipe 23 is appropriately mounted transversely across the moving stairway below the upper run of the steps but above the 60 turn run thereof. The pipe 23 is provided

with a plurality of nozzles 24 (see Figure 5), through which air may be impelled. The nozzles 24 are arranged along the pipe so that they cover the width of the moving steps. One end of the pipe 23 is plugged, as at 25. The other end of the pipe is provided with a hose coupling attachment by means of which a flexible hose 26 may be attached thereto. The flexible hose 26 is connected through a valve 27 to a high pressure compressed air main 28. When the valve 27 is turned on and the flexible hose 26 is connected to the pipe 23, a plurality of streams of air are emitted from the nozzles of the pipe. These streams of air are directed upon the steps, and, as a result, remove therefrom all dust, dirt and other foreign matter. In order to facilitate cleaning the underside of the steps and the inside of the toe-guards 21, as well as the outside of the toe-guards, 70 the pipe 23 may be swivelly mounted so that it may be rotated about its longitudinal axis.

75 A second pipe 30 is mounted transversely across the moving stairway a short distance away from the pipe 23. This second pipe 30 is provided with two downwardly projecting extensions 31 upon each of which is mounted an air nozzle 32. These extensions 31 are arranged so that the nozzles 32 are directly over the driving chains 11. The pipe 30 is provided with a hose coupling attachment by means of which the flexible hose 26 may be attached thereto. As a result, when the flexible hose is connected to the pipe 30 and the valve 27 is turned on, a stream of air is 80 directed against each driving chain to effect the removal therefrom of all dust, dirt and other foreign matter.

85 The lubrication of the step trailer wheels 18 is effected by means of the nozzles 33. Each of these nozzles, constructed as shown in Figure 7, is provided with an air connection 34 by means of which compressed air of a relatively low pressure is fed to the nozzle, and an oil connection 35 by means of which the oil, or other lubricant, is fed to the nozzle. The manner of placement of the nozzles 33 is clearly shown in Figure 4 wherein it may be seen that the nozzles are mounted so that the oil spray is projected angularly 90 upon the step trailer wheels 18. The air supply for the nozzles 33 is obtained by means of the piping 36 which connects with a high pressure compressed air main 37 through the medium of a reducing valve 38 which reduces the pressure to an appropriate value. A valve 40 is provided in the piping adjacent the nozzles 33 in order to control the flow of air thereto. The oil supply for the nozzles 33 is obtained from a tank 41 by means of suitable feeds 42. The tank 41 is open to the atmosphere, so that as a result, the oil feed is dependent on the suction created in the feed lines 42 by the nozzles 33.

100 The lubrication of the driving chains, the 110

chain wheels, and the chain wheel axles is effected by means of nozzles 43. These nozzles are swivelly supported upon the movable carriage 13 so that the spray from each nozzle 5 may be directed alternately against the driving chains and the chain wheels contained therein, and against the chain wheel axles. The nozzles 43 are similar in construction to the nozzles illustrated in Figure 7. The air 10 supply for each nozzle is obtained from the low pressure line 36 through a suitable flexible hose 44. A valve 45 is inserted in the common feed of such hose in order to control the flow of air to the nozzles 43. The oil 15 supply for each of these nozzles is obtained from a tank 46 through the means of a flexible hose 47 in a fashion similar to that described for the nozzles 33.

As a result of the provision of the apparatus above described, the moving stairway may be cleaned and lubricated quickly and readily while it is in operation, and without danger to the worker. The worker may first clean the steps and the toe-guards by 25 connecting the flexible hose 26 to the pipe 23, turning on the valve 27 and imparting a swivelling motion to the pipe 23 while the stairway is in motion. The worker may next clean the driving chains by connecting the 30 flexible hose to the pipe 30 and then turning on the valve 27. He may effect the lubrication of the step trailer wheels by turning on the valve 40. After this is done, the worker may then turn on the valve 45 to 35 effect the lubrication of the driving chain, and then, after a complete trip of the moving stairway, the worker may turn the nozzles 43 so that they effect the lubrication of the chain wheel axles.

40 It has been found that the best results have been obtained when the lubricant employed is a light machine oil and the air pressure is low, of the order of six to twelve pounds per square inch, so as to cause the emission 45 of the oil from the nozzles in a fine, light spray. It has also been found that in addition to the fact that the maintenance of moving stairways is rendered more simple and more effective as a result of the provisions 50 of this invention, that the accident and fire hazards have been reduced, and that the consumption of lubricant by the moving stairway is considerably smaller.

55 As many changes could be made in the above construction and many apparently widely different embodiments of this invention could be made without departing from the scope thereof, it is intended that all matter contained in the above description or 60 shown in the accompanying drawings shall be interpreted as illustrative and not in a limiting sense.

What is claimed is:

1. In combination, a moving stairway having a plurality of steps and a toe-guard for

each step, a pipe mounted transversely across the moving stairway between the upper and lower runs of said stairway, said pipe being mounted to permit partial rotation thereof about its longitudinal axis, a plurality of air nozzles mounted upon said pipe and directed downwardly upon the lower run of said steps, a source of high pressure compressed air, and means connecting said pipe to said source so that said pipe may be oscillated, while said stairway is in operation and air is being forced out through said nozzles, to effect the cleaning of the undersides of all of said steps and said toe-guards as said steps travel by said pipe while in motion on the lower run of said stairway.

2. In combination, a moving stairway having a plurality of steps and driving chains therefor, two pipes mounted transversely across the moving stairway between the upper and lower runs of said stairway, one of said pipes being mounted to permit partial rotation thereof about its longitudinal axis, and being provided with a plurality of air nozzles mounted upon said pipe and directed downwardly upon the lower run of said steps, the other of said pipes being stationarily mounted and being provided with a plurality of air nozzles, one for each driving chain, mounted upon said second pipe and directed downwardly upon the corresponding driving chain while said chain is operating on the lower run of said stairway, a source of high pressure compressed air, a flexible hose connected at one end to said source of compressed air, and coupling means attached to the other end of said hose for detachably connecting said hose to either of said pipes to the exclusion of the other so that said steps may be thoroughly cleaned while said stairway is in operation, and thereafter all dust, dirt, and other foreign matter present upon the driving chains, including that deposited while the steps were being cleaned, may be thoroughly removed while said stairway is still in operation.

3. In combination, a moving stairway having a plurality of steps and driving chains therefor, and means for cleaning and lubricating said driving chains while said stairway is in operation, said means comprising, a pipe mounted transversely across the moving stairway between the upper and lower runs of said stairway, said pipe being stationarily mounted and being provided with a plurality of air nozzles, one for each driving chain, mounted thereupon and directed downwardly upon the corresponding driving chain while said chain is operating on the lower run of said stairway, a plurality of additional nozzles, one for each driving chain, mounted at one end of said stairway and directed at the corresponding driving chain as the steps and driving chain reverse their direction of travel while transferring

from the lower run to the upper run of said stairway, or vice versa, each of said additional nozzles having an inlet for air and an inlet for oil, an open tank containing 5 light machine oil, piping from said tank to the oil inlet for each of said additional nozzles, a source of high pressure compressed air, a source of low pressure compressed air, connection from said source of high pressure 10 compressed air to said transverse pipe, and connections from said source of low pressure compressed air to the air inlet for each of said additional nozzles.

4. In combination, a moving stairway having a plurality of steps, each of said steps having a step trailer wheel mounted at either side thereof; two nozzles mounted between the upper and lower runs of said stairway, one of said nozzles being mounted so as to 20 be directed downwardly and angularly upon the path of the step trailer wheels on one side of the steps as the steps travel along the lower run of the stairway while it is in operation, and the other of said nozzles being 25 mounted so as to be directed downwardly and angularly upon the path of the step trailer wheels on the other side of the steps as the steps travel along the lower run of the stairway while it is in operation, each of 30 said nozzles having an inlet for air and an inlet for oil; an open tank containing light machine oil; piping from said tank to the oil inlet for each of said nozzles; a source of low pressure compressed air; and connections 35 from said source of compressed air to the air inlet for each of said nozzles so that said nozzles are operable to spray a film of light oil upon all the step trailer wheels while the stairway is in operation.

40 In testimony whereof, I have signed my name to this specification.

JOHN WILLIAM GIES.
